FAUCET

Albert C. Mack, East Cleveland, Ohio

Application August 4, 1947, Serial No. 765,941

2 Claims. (Cl. 277—18)

1

This invention relates to a faucet for hot and cold water with a swing-arm spout which is adapted to control the flow of the hot and cold water through the spout, the amount and temperature of the water depending upon the position of the spout.

By using the position of the swing-arm spout to control the temperature as well as the flow of water, the whole operation of turning on and off the water and regulating its temperature is simplified. The arrangement is very desirable for use in barber shops, kitchens and elsewhere.

In the faucet of this invention, the hot and cold water supply lines pass through valves which are actuated by a cam which is so connected with the swing-arm spout that the position of the spout determines the extent to which either or both of the valves is opened or shut. In the preferred arrangement shown in the drawings the spout is adapted to swing through an arc only slightly less than 180° and both valves are closed when the spout is swung to the extreme right and also when the spout is swung to the extreme left.

The invention will be further described in connection with the accompanying drawings in which Fig. 1 is an exploded view of the faucet (omitting one of the valves and its accessories), Fig. 2 is a side view of the body portion of the faucet, Fig. 3 is a plan view of the assembled faucet with an indication of the type of water flow which results when the spout is in different positions, and Fig. 4 is a view in perspective of the cam which operates the valves.

The body 1 is provided with bosses 2 and 3 which are tapped for the reception of pipes carrying hot and cold water, respectively. The flow of the hot and cold water is controlled by valves located in the chambers 4 and 5. The valve for regulation of the cold water is identical with that shown for regulation of the hot water. The latter comprises the valve stem 8 with the valve 9 which seats on the valve seat 10 in the chamber. The valve is held in place by the nut 11 which threads into the top of the chamber 4 and the spring 12 causes the rounded bottom of the valve stem to ride on the surface of the cam 15 and this in turn controls the amount that the valve 9 is lifted from the seat 10. The ring 18 serves as a guide to limit the side movement of the valve in the chamber 4. This guide may be omitted.

Hot water entering the boss 2 passes down through the valve chamber 4 and through the connection 20 into the chamber 21 into which

2

the swing-arm spout fits. The walls of the chamber 21 are tapered downwardly and the body 22 to which the spout 23 is affixed has walls of a complementary taper so that the spout fits snugly in the chamber and no water escapes between its walls and the body portion 22.

The hole 24 passes through the body 22 from one side to the other and is perpendicular to the arm 23. Thus when the swing-arm 23 is in the middle position shown in Fig. 3, one end of the hole 24 opens toward the passage 20 and the opposite end opens toward the corresponding passage which leads from the chamber 5. The semi-circular groove 26 surrounds the body 22 so that there is always communication between the chambers 4 and 5 and the hole 24 for the passage of water from these chambers into the swing-arm 23. As illustrated in Fig. 1, the hole 24 communicates with the bore 27 which leads up through the body 22 and connects with the bore of the swing-arm 23.

The bottom of the body 1 is cut away at 28 to receive the cam 15 which is keyed to the lower portion of the body of the spout by the key 29.

25 The cam is covered by the threaded plug 30 which prevents any leakage from the interior of the faucet. The portion 31 near the bottom of the spout fits into the connecting passage 32 at the bottom of the chamber 21 and the smaller portion 33 fits into the opening 34 in the center of the cam and is keyed to it by the key 29. The nut 35 screws on to the threaded end 36 of the body portion 22 of the spout and holds the cam in place. The nut 35 is rounded and fits into the 30 opening 37 in the center of the threaded plug 30 and turns within it.

Fig. 3 illustrates various positions to which the swing-arm may be turned and these are designated A, B, C, D, E, F and G, respectively. In 40 the positions A and G both the hot and cold water valves are closed. In the positions B and C the cold water valve is closed and the hot water valve is partially opened and fully opened, respectively. In the position D the hot and cold water valves are both open and may be wide open or only partially open. In the positions E and F the hot water valve is closed and the cold water valve is fully opened and partially opened, respectively.

50 The opening of the valve is controlled by the cam 15. When the unit is assembled the high portion of the cam 40 is located directly below the swing-arm 23. The cam turns with the swing-arm. When the swing-arm is turned to the position A (Fig. 3) the stem of the hot water

valve located in chamber 4 abuts against the left-hand side of the raised portion 40 so that the swing-arm can be moved no further in this direction. Similarly, the stem of the valve in the chamber 5 for the cold water abuts against the right-hand side of the raised portion 40 when the swing-arm is moved to the position G, so that this is as far as the swing-arm can be turned in this direction.

As the cam is moved it raises and permits the lowering of the stems of both the hot and cold water valves which bear on diametrically opposite portions of the cam. To simplify the explanation, when one of the valve stems is pressed by the spring 12 (or the corresponding spring of the other valve) against a thin or low portion of the cam the valve closes against the seat in the valve chamber. No water can then pass through the valve into the swing-arm. On the other hand, when a thick or high portion of the cam 15, is moved under a valve stem, the valve is lifted from its seat. The amount that the valve is opened depends upon the height of the portion of the cam which is under the valve stem.

To facilitate understanding of the cam, in Fig. 4, the top surface is divided into sections which are lettered with the same letters used in Fig. 3. For instance, the two letters A indicate the surfaces of the cam which are below the respective valve stems when the swing-arm is in the position indicated as A in Fig. 3. The surface A adjacent the high portion 40 is below the stem of the hot water valve and the opposite portion of the cam which also bears the letter A is below the stem of the cold water valve. Both portions of the cam lettered A are thin and, therefore, both valves are closed. When the swing-arm is moved to the position B of Fig. 3 the stem of the hot water valve rides up the inclined surface B and the hot water starts to flow. The surface B below the stem of the cold water valve is on the same level as the surface A adjoining it and the cold water valve remains closed. When the swing-arm is moved to the position C the stem of the hot water valve is lifted further so that this valve is wide open. The opposite surface C is on the same level as the adjoining surface B so that the cold water valve remains closed. The surfaces D on opposite sides of the cam are of the same height and may be the same height as the surface C on the left-hand side of the valve or a trifle lower. Both valves are, therefore, fully or partially opened when the arm is in position D (Fig. 3). The portions of the cam surface marked E, F and G correspond to the positions C, B and A on the cam, respectively, but are on opposite sides of the cam and operate the opposite valve.

Thus it is seen that in this faucet the movement of the spout is utilized to regulate the amount and temperature of the water. The positions indicated in Fig. 3 are illustrative only and do not limit the positions to which the swing-

arm may be moved because the swing-arm may be turned to any position between A and G. Thus, the water may be turned off entirely by swinging the spout to either side, and at the intermediate positions different amounts of water are obtained and the temperature of the water is controlled.

It is to be understood that the invention is not limited to the specific arrangement shown, as other types of valves and other means for operating the same may be employed. The faucet may be constructed of brass or other suitable material.

What I claim is:

1. A faucet for hot and cold water which comprises a body portion in which are two valve chambers and a chamber for the body of a swing-arm spout, hot and cold water lines leading to the respective valve chambers, a connection in said body portion between each valve chamber and the chamber for the body of a swing-arm spout, a swing-arm spout with a body which fits into the body chamber, a cam fastened to the bottom of said body and adapted to move with it, and in each valve chamber a valve mounted on a valve stem and a spring which tends to seat the valve and causes the bottom of the valve stem to press on to the surface of the cam and be operated by its movement.

2. A faucet for hot and cold water, a chamber therein which is circular in cross section and gradually tapers inwardly, a swing-arm spout the body of which fits snugly in the chamber, there being an opening in the bottom of the chamber and an extension on the bottom of the body extending therethrough, a cam fastened to said extension and movable therewith, the upper portion of the body being hollow, a groove which encircles the body at the bottom of the hollow portion, openings from the groove to the hollow, two valve chambers in the faucet and openings therefrom into the aforesaid chamber at the level of said groove, hot and cold water lines leading to the respective valve chambers, a valve seated in each chamber, and a stem on each valve extending through the openings defined by the respective seats and contacting the cam whereby the movements of the valves are controlled by the movement of the cam.
